(57) CLAIM

I claim the ornamental design for a personal care product, as shown and described.

DESCRIPTION

FIG. 1 is a front perspective view of a personal care product showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is an alternate top view thereof;

FIG. 9 is an alternate bottom view thereof; and,

FIG. 10 is rear perspective view thereof.

The dash broken lines shown in the drawings illustrate portions of the personal care product and form no part of the claimed design.

1 Claim, 10 Drawing Sheets
